SOAP DISPENSER

William H. Wallo, Skokie, Ill.

Application October 13, 1954, Serial No. 462,023

6 Claims. (Cl. 222—531)

My invention relates to dispensing devices and particularly to a dispensing device usable with boxes containing granular materials such as, for example, the well known household soaps and detergents.

The boxes in which granulated soaps and similar materials are normally sold almost universally have a perforated or similarly weakened area adjacent the upper portions of one of their side walls. The housewife normally presses this weakened area inwardly to create an opening in the box from which she may pour the granular materials contained therein. It is accordingly one object of my invention to provide a simple and easily operated device for use with such boxes which may permit the creation of a control opening through which to pour the material and will at the same time provide a means for closing the box when not in use to prevent spilling.

Another purpose is to provide a dispensing device for granular materials for use with such boxes wherein a portion of the device is effective to prevent the device from slipping out of contact with the box when the device is used.

Another object is to provide a granular soap-dispensing device having an element effective to position a portion of the box, which normally would tend to close an opening in the box, in non-closing position when the device is in operation.

Another purpose is to provide a dispensing device which is simple in construction and economical to manufacture and a device which in itself has no moving parts, but which is designed for movement relative to the box on which it is used.

Another purpose is to provide a soap-dispensing device which may be easily and readily attached to a box containing granular soap or other granular materials.

Another object of my invention is to provide a soap-dispensing device which may be retained on the box in which the soap is packaged and a device including a pair of members adapted to clamp a portion of the box therebetween.

Other objects will appear from time to time in the course of the specification and claims.

I will illustrate my invention more or less diagrammatically in the accompanying drawings wherein:

Figure 1 is a perspective view illustrating my device as attached to a package.

Figure 2 is a side view in cross-section and on an enlarged scale taken on the line 2—2 of Figure 1.

Figure 3 is a view similar to that of Figure 2 and showing my device in another position relative to the box.

Figure 4 is a front elevation on a scale reduced over that of Figures 2 and 3.

Figure 5 is a view taken on a line 5—5 of Figure 4.

Figure 6 is a rear elevation; and

Figure 7 is a view taken on a line of 7—7 of Figure 4.

Like parts are indicated by like numerals throughout the specification and drawings.

2

Referring now to the drawings and particularly to Figure 1, the numeral 1 generally indicates a soap package or box containing some form of granular materials such as soap or cereals, etc. The box 1 has a top wall 2, a side wall 3, and a front and rear wall, the front wall being partially shown as at 4.

Continuing to refer to Figure 1 which shows my soap-dispensing device as attached to the package 1, the numeral 5 generally designates a top wall of my device. A front wall of my device is illustrated at 6. A pair of rearwardly extending parallel side walls 7, 8 are positioned to lie along and against the front and rear walls respectively of the box 1. The front wall 6 may be cut as indicated generally at 10 in Figure 4, the cut 10 comprising a pair of parallel spaced vertical cuts and a single horizontal cut adjacent the bottom edge of the front wall 6, thus forming the front wall in the shape of a frame. The lower horizontal portion of the front frame wall 6 may be upset rearwardly as indicated generally at 12 to create a type of pressure member against the side wall 3 of the box 1. The central portion 15 of the wall 6 within the cut 10 may be rearwardly bent as indicated generally at 13 and may serve as a type of spring arm or a springlike finger.

The bottom edge of the central portion 15 within the cut 10 of the wall 6 may be rearwardly bent slightly as indicated generally at 16 in Figure 2 in order to provide for ease of insertion through an opening 17 in the box 1. The wall 3 of the box may include an upper portion 3a which is inwardly bent to create the box-opening 17 as indicated generally at Figures 1, 2 and 3. The spring-like wall portion 15 of my device may in turn have a cut-out or dispensing window or opening 20 positioned somewhat in the center thereof. A portion of that part of the wall 15 which was cut to form the opening 20 may be rearwardly bent along the upper edge of the cut-out 20 as indicated generally at 21 in Figure 2, the purpose of which will appear hereinafter.

It will be realized that whereas I have described and illustrated a practical and operative device, nevertheless, many changes may be made in the size, shape, number and disposition of parts without departing from the spirit of my invention. I, therefore, wish my description and drawings to be taken as in a broad sense illustrative or diagrammatic, rather than as limiting me to my precise showing.

The use and operation of my invention are as follows:

The user, in order to insert my device, merely presses inwardly on the box portion 3a to create the opening 17 in the side wall 3 of the box 1. The user then merely inserts the lower inwardly bent portion 16 of the central wall portion 15 into the opening from above. The device is then slid downwardly, the upper portion of the box wall 3 immediately adjacent and below the box-opening 17 being gripped between the back face of the frame wall 6 and the front face of the center wall portion 15, which acts as a spring-like finger, to clamp the box wall 3 therebetween. As illustrated in Figure 2, when the device is pressed its full length downward until the top wall 5 of the device rests upon the top wall 2 of the box, the opening 17 in the box is completely sealed off and it is impossible for spillage of the granular material within the box 1 to occur.

When the user desires to pour material from the box 1 it is necessary only that the device be raised until the opening 20 in the spring-finger wall portion 15 is brought into alignment with the opening 17 in the box 1. As best seen in Figures 2 and 3, as the device is raised upwardly, the inwardly bent portion 21 contacts the box portion 3a and forces it rearwardly away from the box opening 17 thus preventing any jamming of the material

or closing of the opening 17. In addition, the inwardly bent portion 21 acts as a stop means to prevent the device from being lifted too far upwardly so as to move the opening 20 beyond the opening 17 in the box 1 or to cause the device to slip out of engagement with the box.

It will be realized that the user can control the size of the opening from which material will flow by controlling the amount of the opening 20 which is placed in alignment with the opening 17 in the box 1. This is controlled easily and simply merely by gauging and controlling the height of the top wall 5 of my device above the top wall 1 of the box.

I claim:

1. For use with a box having an opening adjacent an upper portion of the side wall thereof, a dispensing device for granular materials contained within the box, said device comprising a front wall adapted to engage and slide along said box side wall, a top wall adapted to seat upon the top wall of said box when the device is in its lowermost position, and a pair of side walls adapted to engage and slide along the front and rear walls of said box, a central wall portion spaced inwardly from said front wall and adapted to pass through said box opening, said last named wall being spaced inwardly from said front wall a distance less than the thickness of the side wall of said box whereby said side wall will be gripped between the outer surface of said last named wall and the inner surface of said front wall, and an opening in said last named wall portion spaced downwardly from the upper edge thereof, said last named wall portion having an inwardly bent portion along the upper edge of said wall opening said last named wall opening being positioned for alignment with the opening in said box when said device is raised upwardly a distance sufficient to place said inwardly bent portion in engagement with a portion of said box normally in alignment with said box opening.

2. A soap dispensing device for rectangular boxes comprising a body portion slidably mounted on the side wall of said box, said body portion having an upper wall adapted to seat on the top wall of said box and to limit the downward movement of said device, said device having a spring arm central portion adapted to pass through

an opening in said box and to grip the side wall of said box between said body portion and said spring arm, said spring arm having an opening therein positioned below the opening in said box when said device is in its lowermost position, said opening being positioned in said spring arm to cause alignment with the opening in said box when said device is slidably moved upwardly along said side wall.

3. The structure of claim 2 characterized by and including an inwardly bent portion on said spring arm along the upper edge of said opening and adapted to limit the upper movement of said device.

4. The structure of claim 2 characterized by and including an inwardly bent portion along the upper edge of said opening in said spring arm adapted to contact a portion of the side wall of said box which would normally be in alignment with the opening in said box, and to force said box side wall portion inwardly and upwardly out of alignment with said opening.

5. The structure of claim 2 characterized by and including an inwardly bent lower edge portion on said spring arm adapted to facilitate the attachment of said device to said box by the passage of said spring arm through said box opening.

6. A soap dispensing device having means for controlling the size of the soap dispensing opening, including a body portion adapted for slidable movement along the side wall of a box having an opening, an elongated spring arm wall portion extending through said opening and clamping said box side wall between said body portion and said spring arm, an opening in said spring arm below the central portion thereof, but substantially spaced from the lower edge thereof, whereby said device may be moved upwardly along said side wall to place the opening in said spring arm in various degrees of alignment with the opening in said box while retaining said device on said side wall whereby the size of the opening to which the material may be dispensed from said box is controlled.
